CLAIM

The ornamental design for a lid for weatherproof storage tote, as shown and described.

DESCRIPTION

FIG. 1 is a top perspective view of a lid for weatherproof storage tote;

FIG. 2 is a bottom perspective view thereof;

FIG. 3 is a top plan view thereof;

FIG. 4 is a front elevational view thereof;

FIG. 5 is a right side elevational view thereof; and,

FIG. 6 is a bottom plan view thereof.

A left side elevational view is not shown because it is a mirror image of the right side elevational view. A rear side elevational view is not shown because it is a mirror image of the front side elevational view. The ornamental design which is claimed is shown in solid lines in the drawings. The broken lines depict portions of the lid for weatherproof storage tote that form no part of the claim.
